(57) **CLAIM**

The ornamental design for a wall cabinet, as shown and
described.

DESCRIPTION

FIG. 1 is a right front perspective view of a wall cabinet
showing our new design;

FIG. 2 is an enlarged fragmentary front elevation view of FIG.
3; and,

FIG. 3 is a front elevation view of the wall cabinet of FIG. 1.
The ornamental design is not visible in a rear view, top plan
view or bottom views. Those portions of wall cabinet in
broken lines are understood to form no part of the claimed
design.

The characteristic feature of the ornamental design resides in
the use of a pattern on the wall cabinet doors. One embodiment
of a pattern according to the ornamental design is shown
in FIGS. 1-3.
